C. C. STIRLING.
SNAP SWITCH,
APPLICATION FILED OCT. 19, 1917.

1,267,604.

Patented May 28, 1918.

UNITED STATES PATENT OFFICE.

CLARENCE C. STIRLING, OF HARTFORD, CONNECTICUT, ASSIGNOR TO THE HART & HEGEMAN MANUFACTURING COMPANY, OF HARTFORD, CONNECTICUT, A CORPORATION OF CONNECTICUT.

SNAP-SWITCH.

1,267,604.

Specification of Letters Patent.

Patented May 28, 1918.

Application filed October 19, 1917. Serial No. 197,422.

To all whom it may concern:

Be it known that I, CLARENCE C. STIRLING, a citizen of the United States, residing at Hartford, in the county of Hartford and State of Connecticut, have invented certain new and useful Improvements in Snap-Switches, of which the following is a specification.

This invention relates to snap switches and especially to that type involving the use of but a single element, generally manually operable, for effecting through suitable means, the necessary movement of the switching member, the primary purpose of the invention being the provision of an article of this character which is compact, simple in construction and by which the necessary movement can be accomplished in an easy and ready manner.

In the drawings accompanying and forming part of the present specification I have shown in detail a form of embodiment of the invention. This I will set forth in the following description. I do not, however, necessarily limit myself to this particular disclosure; I may depart therefrom in several respects within the scope of the invention defined by the claims following said description.

Referring to said drawings:

Figure 1 is a front elevation of a switch involving the invention.

Fig. 2 is a vertical sectional view of the switch.

Fig. 3 is a diagonal section on the line 3-3 of Fig. 2, looking in the direction of the arrow.

Figs. 4 and 5 are cross sections on the lines 4-4 and 5-5 respectively of Fig. 3, looking in the direction of the arrows applied to the respective lines.

Like characters refer to like parts throughout the several views.

The different parts of the switch may be supported in any desirable manner. The support shown for this purpose comprises a base 2 and a shell or casing 3. The base 2 is generally made from some insulating substance while the shell 3 is usually of metal receives within its open side the base, the two parts being united together in any desirable manner as by screws 4. The shell or case 3 is customarily furnished with an insulating lining such as that denoted in a

general way by 5 and which in effect conforms to the interior shape of the shell.

Within the casing or housing is a switching member such as that denoted in a general way by 6. This switching member as will hereinafter appear is mounted for movement about an axis, being preferably oscillatory. It may consist of an elongated strip of strap-metal laterally bent at its ends to present the practically duplicate terminals 7 which are equidistantly disposed from the center of motion of the switching member. The base 2 may have fastened thereto the L-shaped or angular bracket or equivalent support 8, to the off-standing arm of which the switching member 6 is pivoted as at 9, the pivot and as a result the switching member being held in position against accidental displacement by a nut as 10 fitted to the threaded portion of the pivot 9.

Fastened to the base 2 are the two lipped members 11 which are separated to receive between them the adjacent contact portion 7 of the switching member 6 when the switch is on as shown for instance by dotted lines in Fig. 2. The bases of these members 11 are superimposed as shown for example in Fig. 3, and the inner one of them rests against the inner face of the base 2, the several parts being perforated to receive the screw 12 around the outer end of which may be coiled the wire which is held in position by the nut 13 threaded onto the screw 12 constituting a suitable connection member. The complementary contact is denoted by 14 and it may consist of comparatively similar members united with the arcuate shank 15 which follows the curvature of the lining 5 and which has an inturned foot 16 perforated for the passage of the screw 17 receiving the nut 18, the screw 17 constituting suitable wire connecting means, the wire being held in position by the nut 18 on said screw. It will be clear, therefore, that when the terminals of the switching member 6 engage the mating contacts 11 and 14 as shown for illustration by dotted lines in Fig. 2, the switch will be in the on position or the circuit closed.

There is an actuator for a switching member as 6, and it will be understood, of course, that the switching member in the present case is moved between its on and off positions

- by this single actuator as 19. Said actuator comprises an elongated finger portion extending through the registering arcuate slots 20 and 21 formed in the shell 3 and lining 5 respectively, the ends of the slot 20 constituting stops to maintain the actuator 19 in the two positions thereof. For ease in understanding the invention I have shown the actuator as only occupying one of its 10 positions in Fig. 2 but have shown the switching member in both positions, however, in said view. The actuator 19 has at its inner end a hub 23 from which there extends outward the pivot 24 projecting through the 15 off-standing portion of the bracket or bearing 25 united by a screw as 26 to the base 2. The threaded part of the screw 24 receives the nut 27 to hold the actuator in assembled relation.
- 20 The actuator 19 does not in the present case directly operate the switching member 6, acting through the intervention of yieldable or resilient means such as the spring 28 which is of loop-like form. This spring 28 is set in a notch 29 in the hub 23 and its coiled body 30 receives the stud 31 supported by the hub and extending across the notch 29. The side branches of the spring first 25 normally converge outward, then diverge 30 and then cross, the crossed portions of the branches of the spring engaging opposite faces of the switching member and being normally or when the switching member is at rest, at opposite sides of the center or axis 35 of oscillation thereof as shown for illustration by Fig. 3. It will be assumed that the switch is in the off position as shown for instance by full lines in Fig. 2, and that it is desired to close the circuit. In this event 40 the finger piece or manually operable portion 19 will be swung in the direction of the arrow near the free end thereof. As the finger piece thus moves, the hub 23 of course, is rocked therewith, carrying the spring also 45 therewith and the free ends of the spring rolling across the switching member 6. The bearing portions 32 of the spring during this time roll upon the switching member which causes the uncrossing of the crossed portions 50 of the spring just about the time the free portions of the spring reach a line corresponding to the center of motion of the switching member, the result being that as soon as this line is crossed, the switching 55 member will be at once snapped to the full line position shown in Fig. 2 by the side branches of the spring.
- In Figs. 4 and 5 I have indicated by arrows the motions of the parts. As the free portions of the spring 28 move with the rocking actuator 19 they roll along opposite faces of the switching member and are uncrossed and open just before the center of motion is reached. When this line is crossed, the spring arms ride rapidly along opposite 60 faces of the switching member, and thus snap it to its extreme position, and when the motion is finally completed, the spring arms will be again crossed but reversely to what they were before. I have described but one motion of the parts. It will be understood that the opposite motion is the same in action but merely a reversal.
- It will be clear that in the construction shown and hereinbefore described, I provide a spring to produce a rapid or snapping action of a switching member as 6 which as a matter of preference takes the form of a contact lever. This spring is so held and shaped that the ends thereof alone are used to obtain the necessary movement of the switching member to cause it to assume in succession the on and the off positions. This spring is so shaped that its ends are crossed, these ends engaging opposite faces of the switching member or contact lever and being free to turn, owing to the fact that a pin as 31 is passed through the coiled body of the spring. These crossed ends or portions of the spring are free to open or expand, and they uncross and are recrossed by their own action on the movement of the hub or equivalent part 23. In this hub or rather in a notch or slot 29 therein is set the coiled body to which I have referred, and through it passes said pin 31. In effect, therefore, the spring or the branches thereof are permitted to float laterally and comparatively freely, so that they can exercise the necessary and desired functions. The branches or sides of the springs are at practically right angles to the axis of the coiled body of the spring, and these branches are crossed and rest against opposite faces of the switching member at opposite sides of the center of motion. The result is that the spring has a degree of freedom necessary to secure successive crossing and recrossing of its branches or sides.
- What I claim is:
1. A snap switch comprising an oscillatory switching member, and actuating means for imparting a snap movement to the switching member, comprising two yieldable members to engage opposite faces of the switching member and to travel along said faces between stations at opposite sides of the center of oscillation of the switching member.
  2. A snap switch comprising an oscillatory switching member, and actuating means for imparting a snap movement to the switching member, comprising two yieldable arms to engage opposite faces of the switching member and to roll along said faces between stations at opposite sides of the center of oscillation of the switching member.
  3. A snap switch comprising an oscillatory switching member, and actuating means for the switching member comprising

two spring arms to engage opposite faces of the switching member and to travel along said faces between stations at opposite sides of the center of oscillation of the switching member.

4. A snap switch comprising an oscillatory switching member, and actuating means for imparting a snap movement to the switching member, comprising two spring arms to engage opposite faces of the switching member and to roll along said faces between said stations at opposite sides of the center of oscillation of the switching member.

15 5. A snap switch comprising an oscillatory switching member and actuating means for the switching member, comprising two crossed spring arms to engage opposite faces of the switching member and to

20 roll along said faces between stations at opposite sides of the center of oscillation of the switching member, the rolling of the arms reversing their relation to each other.

25 6. A snap switch comprising a switching member, an oscillatory actuator having a notch, a spring set in the notch and provided with two crossed branches, the free portions of which roll along opposite faces of the switching member between stations 30 at opposite sides of the center of oscillation thereof, to thereby snap the switching member between on and off positions.

35 7. A snap switch comprising a movably mounted switching member, and actuating means for the switching member comprising two arms to traverse opposite faces thereof to snap the same between on and off positions.

40 8. A snap switch comprising an oscillatory switching member, an actuator pro-

vided with a hub having a slot, the actuator being mounted to turn about an axis extending through the hub, a coiled spring set in the slot, the sides of the spring extending from the hub, being normally crossed and 45 engaging opposite faces of the switching member at opposite sides of the axis of oscillation thereof, and a pin extending through the coiled body of the spring to permit free lateral movement of the 50 branches thereof, said sides as the hub is moved from one extreme position to the other rolling across opposite faces of the switching member, uncrossing during their rolling movement, and recrossing to a position 55 reverse to that they last occupied to thus snap the switching member from one position to another.

9. A snap switch comprising an oscillatory switching member, an actuator mounted to turn about an axis, spring means connected with the actuator and to move therewith, the sides of the spring extending from the actuator, being normally crossed and 60 engaging opposite faces of the switching member at opposite sides of the axis of oscillation thereof, said sides as the actuator is moved from one extreme position to the other rolling across opposite faces of the 65 switching member, uncrossing during their rolling movement and recrossing to a final position reverse to that they last occupied by their own action to thus snap the switching member from one position to another.

In testimony whereof I affix my signature 75 in the presence of two witnesses.

CLARENCE C. STIRLING.
